UNITED STATES PATENT OFFICE.

JAY GRIFFITH McDOWELL, OF SHARON, PENNSYLVANIA.

CONDENSER AND SEPARATOR FOR COMPRESSED AIR.

1,366,403.

Specification of Letters Patent. Patented Jan. 25, 1921.

Application filed August 25, 1919. Serial No. 319,658.

To all whom it may concern:

Be it known that I, JAY GRIFFITH McDowell, a citizen of the United States, residing at Sharon, in the county of Mercer 5 and State of Pennsylvania, have invented certain new and useful Improvements in Condensers and Separators for Compressed Air, of which the following is a specification, reference being had to the accompanying drawings.

This invention relates to compressed air apparatus, and particularly to means for removing moisture and grit from compressed air.

15 The general object of my invention is to provide mechanism operating automatically to remove from compressed air or other fluid the moisture thereof and any grit, dust or other foreign matter which might be carried into the separator by the compressed air or other fluid.

A further object is to provide a mechanism of this character including a receptacle into which moisture is discharged, so 25 mounted that when a predetermined quantity of liquid has collected in this receptacle, the liquid may be automatically discharged therefrom.

A further object in this connection is to 30 provide a receptacle of the character described which is vertically shiftable and which is normally held in a predetermined receiving position by a counter-weight, and which, when a predetermined amount of 35 liquid has gathered in the receptacle, will descend against the action of said counter-weight, and in descending will cut off communication with the interior of the condensing and separating chamber and will 40 open automatically a discharge valve permitting the draining of the receptacle, the return movement of the receptacle causing the cutting off or closing of the discharge valve and the opening of communication between the receptacle and the interior of the 45 separating tank.

Other objects will appear in the course of the following description.

My invention is illustrated in the accompanying drawings, wherein:—

Figure 1 is a side elevation of a mechanism constructed in accordance with my invention, showing in full lines the discharging position of the mechanism and in dotted lines the normal or receiving position thereof;

Fig. 2 is a vertical sectional view on the line 2—2 of Fig. 1 with the parts in their discharging position;

Fig. 3 is a vertical sectional view on the line 3—3 of Fig. 2 but showing the parts in their receiving position;

Fig. 4 is a sectional view through one end of one of the members 22, showing the detail 39 partially in section;

Fig. 5 is an elevation of the tubular valve 19;

Referring to these drawings, 10 designates the outer cylindrical wall of a condensing and separating chamber having an inlet pipe 11 and an outlet pipe 12, the latter being located at the upper end of the chamber and extending to any suitable discharge point from a cap 13 having screw-threaded engagement with the wall 10. 15 The bottom of the chamber is formed by a plate of head 14, and disposed within the chamber between the top and bottom thereof are a plurality of cone-shaped screens 15 of fine wire mesh supported by a series of sleeves 15^a. The compressed air enters at the inlet 11, passes upward through the screens, which act as filters, and out through the outlet pipe 12. This compressed air is expanded when it enters the chamber 10 20 and, therefore, the moisture in the air condenses within the chamber 10. This moisture and the dirt or grit which is carried in by air are separated by the screens which thus permit the dry air to pass through to 25 the outlet while the water and grit drop to the bottom of the tank by gravity. For the purpose of receiving the water and grit and automatically discharging them, I have 30 provided the mechanism now to be described.

Below the bottom 14 there is disposed a receptacle 16, illustrated as globular in form, though it might be of any suitable shape, and having an exteriorly screw-threaded neck 17.

Extending downward from the bottom 14 is a T 18, open at its ends, and having its medial branch screw-threaded into the bottom 14. Rotatably disposed within the 105 horizontal portion of this T is a rotatable, cylindrical, tubular valve 19, which is open at its ends and exteriorly screw-threaded at its ends, the screw-threads on one end being reverse to the screw-threads on the opposite 110 end. This tubular valve 19 is long enough to extend at each end beyond the open ends

of the T 18 and is provided at its middle with a port 20 which, when the tubular valve is rotated a quarter turn, is adapted to register with a port 21 formed in the 5 valve casing or T 18. When the valve 19 is in its normal position, the port 20 opens into the upwardly extending branch of the T and receives moisture which is discharged from the lower end of the container 10.

10 It will be understood that the tubular valve 19 is rotatable within the T 18 and is so formed that it has air-tight engagement therewith. Screwed on the ends of the tubular valve 19 are the U -shaped members 22, the tubular valve being provided with a head 23 whereby it may be rotated by means of a wrench. Engaging the outer ends of these U -shaped bends 22 is a tubular valve 24 which is also reversely screw-threaded 20 at its ends for engagement with the ends of the U -shaped bends 22 and is provided at its middle with a port 25. This tubular valve 24 rotates within a valve casing or T 26 having a downwardly extending medial 25 branch 27 interiorly screw-threaded for engagement with the neck 17 of the receptacle 16. Mounted loosely on the valve casing 18 is a pulley 28 over which is disposed a flexible cord or wire 29 having a counter-weight 30 at one end. The opposite end of this cord is attached to the valve casing 26 by means of a band or clip 31.

The lower end of the collecting receptacle 16 is provided with a valve 32 which is normally closed, but when moved upward, will discharge water therefrom. Preferably, this valve is formed with a float 33 adapted to open when a predetermined quantity of water has collected within the receptacle. 35 Preferably, this float is assisted in its opening by the valve being provided with a valve stem 34 adapted to come in contact with the lower, angularly bent end 35 of a rod 36 which is attached to the bottom 14 and depends therefrom. This mechanism, it will be seen, is such that normally the counter-weight 30 holds the free end of the valve structure upward as in Fig. 3, thus closing communication between the port 20 and the 40 port 21 and opening communication between the air chamber 10 and the interior of valve 19 so that liquid may flow into the valve 19 and through the bends 22 into the valve 24. The casing 26 being rotatably mounted upon 45 the valve 24 and having its projecting branch 27 always vertical, it follows that when the valve 24 is in approximately the same horizontal plane as the valve 19, the port 25 will be out of register with the discharge branch 27 of the valve casing. When, however, sufficient water has 50 collected within the parts formed by the valve 19, the bends 22, the valve 24, and the receptacle 16, the weight of the water will 55 overcome the resistance of the counter-

weight 30 and the valve structure will swing downward, the valve 19 acting as an axis for this swinging movement, and this will cause the ports 20 and the upwardly extending branch of the valve casing 18 to move 60 out of register with each other while the ports 20 and 21 come into register. Thus, communication is cut off between the valve structure and the chamber 10 and at the same time the port 21 is opened so as to permit 65 the discharge of compressed air from the interior of the casing. The same movement of the valve structure causes the port 25 to move out of register with the branch 27 and the downward movement of the receptacle 70 16 after it reaches a certain point causes the upward movement of the valve 32 to discharge the water from chamber 16.

Now it is imperative to prevent the downward movement of this valve structure and 75 the receptacle 16 until the receptacle is full of water or the water has reached a predetermined point therein. To this end, I provide a detent 37 which engages with a notch 80 38 formed in the upper end of one of the bends 22, this detent 37 being mounted within a socket 39 formed in the angular upper end of a rod 40 and urged outward by a spring 41. The lower end of this angular rod 40 has attached thereto a pivoted 85 counter weight 42 which resists any movement of the rod 40. It will be seen that this 90 detent with the rod 40 will tend to prevent any rotary movement of the bend 22 having the notch 38 until the weight of water within the receptacle 16 is so great as to overcome the weight 42, whereupon the valve casing 19 with the bends 22 will rotate, as before described, from their raised to their lowered positions. As soon as the notch 95 38 has sprung past the detent, the detent will swing back into position again, and when the water has been discharged from the receptacle 16, the counter-weight 30 will turn the parts in their initial position and the 100 detent 37 will be forced inward against the action of the spring 41 until the detent bears again against the notch 38 when the parts are in position to receive water from the 105 separating chamber 10. It will be understood that the weight 30 is just heavy enough to carry the valve mechanism and the receiver 16 back into their raised positions 110 when the water has been discharged from the receiver. The weight of the counter- 115 weight 42 is a little less than the weight of the water in the receiver.

It will be seen that this device is entirely 120 automatic in its action, and that by this means the water and grit or other foreign 125 matter collected within the chamber are automatically discharged from time to time, thus preventing the chamber 10 from becoming filled with water or foreign matter. The mechanism is simple, may be easily ap- 130

plied and easily assembled and disassembled. It is adapted to be used wherever it is desired to separate compressed air from the moisture and grit which may be carried 5 therein. Of course, from time to time the receptacle 10 may be blown out by means of the blow-out cock 43.

While I have illustrated a form of my invention which I believe to be thoroughly 10 effective and which has relatively few parts, I do not wish to be limited to this, as the principle of the invention might be applied in many different ways. Thus, the shape of the receiving vessel or receptacle 16 might 15 be readily changed, the shape of the discharge valve might be changed, and the means for resisting the downward movement of the receiver or receptacle 16 might be varied without departing from the spirit of 20 the invention as defined in the appended claims.

While I have heretofore referred to the use of my invention for the purpose of removing grit and moisture from compressed 25 air, I do not wish to be limited to this, as the mechanism might also be used to remove dirt and moisture from gases such as natural and artificial fuel gases, gases used for welding, etc., in other words it might be used 30 for eliminating moisture and foreign particles from any vapor or gas.

I claim:—

1. A mechanism of the character described including a chamber having a liquid outlet, 35 a vertically movable receptacle into which the liquid outlet discharges and having an outlet valve, a counterweight yieldingly supporting the receptacle in a receiving position but yielding upon the collection of a 40 predetermined quantity of liquid within the receptacle to cause the descent of the receptacle and the opening of the outlet valve, the descent of the collecting receptacle automatically acting to cut off communication 45 between the receptacle and the said chamber, and a yielding detent yieldingly impeding the downward movement of the receptacle until the weight of the receptacle and the water therein overcomes the detent.

50 2. A mechanism of the character described including a chamber, a tubular open-ended valve casing attached to the bottom of the chamber and communicating with the interior thereof, a tubular valve rotatably mounted within said casing and having a port which, when the valve is disposed in one position, communicates with the chamber, approximately U-shaped bends connected to the end of said valve and extending 55 therefrom, a tubular open-ended valve connected to the opposite ends of said bends, and a valve casing loosely surrounding the last named tubular valve and having a branch extending at right angles therefrom,

a collecting receptacle engaging said branch, 65 a valve in the bottom of the receptacle, counter-weighted means tending to swing the second named valve and its casing into the same horizontal plane as the first named valve and its casing, and means for causing 70 the opening of the outlet valve and receptacle when the weight of accumulated water therein swings the receptacle and valve structure downward, and means yieldingly detaining the valve structure and receptacle 75 in their raised positions.

3. A mechanism of the character described including a chamber, a liquid collecting receptacle, a tubular member pivotally connected to the chamber and to said receptacle and 80 forming a conduit between the receptacle and the chamber, said tubular member when it is in an approximately horizontal position connecting the receptacle to the chamber and when it is in a depressed position cutting 85 off communication between the chamber and the receptacle, a normally closed outlet valve in the receptacle opening upon a descent thereof to discharge the contents of the receptacle, a counter-weight operatively connected to the tubular member, yieldingly holding it in a horizontal position but permitting its descent when counter-balanced by a sufficient weight of water in the receptacle, and a counter-weighted detent yieldingly resisting the downward movement of 90 the receptacle until sufficient weight of water has accumulated therein. 95

4. A mechanism of the character described including a chamber, a liquid collecting receptacle, a tubular member pivotally connected to the chamber and to said receptacle and forming a conduit between the receptacle and the chamber, said tubular member when it is in an approximately horizontal 100 position connecting the receptacle to the chamber and when it is in a depressed position cutting off communication between the chamber and the receptacle, a normally closed valve in the receptacle opening upon 105 a descent thereof to discharge the contents of the receptacle, a counter-weight operatively connected to the tubular member, yieldingly holding it in a horizontal position but permitting its descent when counter-balanced by a sufficient weight of water in the receptacle, said counterweight being just sufficient to counterbalance the receptacle and its allied parts but not sufficient to counterbalance the receptacle when liquid has 110 collected therein, and a counter-weighted detent adapted to yieldingly resist the downward movement of the receptacle until sufficient weight of water has accumulated therein, said detent comprising an angular rod 115 pivotally supported at its upper end and having a counter-weight at its lower end, the upper extremity of the angular rod hav-

ing a spring-pressed detent projecting therefrom, said tubular member having a tooth with which the detent engages.

5. A mechanism of the character described including a vertically movable receptacle adapted to receive liquid and having an outlet valve, a counterweight yieldingly supporting the receptacle in a raised and receiving position but yielding upon the 10 collection of a predetermined quantity of liquid within the receptacle to permit the descent of the receptacle and the opening of the outlet valve, a member moving with the receptacle as it falls or rises and having a tooth, and a yielding detent engaging said tooth and yieldingly restraining the movement of said receptacle until the weight of the receptacle and the water therein overcomes the detent.

20 6. A mechanism of the character described including a chamber having a liquid outlet, a vertically movable, swingingly mounted receptacle into which said liquid outlet discharges, said receptacle having an outlet valve normally closed but automatically opened by the descent of the receptacle to a predetermined position, a counterpoise yieldingly supporting the receptacle in a raised receiving position, said counterpoise having a weight only slightly greater 25 than the weight of the receptacle itself to cause the return upward movement of the receptacle when the water has been completely discharged therefrom whereby said 30 receptacle will remain lowered until all the liquid has been discharged therefrom, and means impeding the downward movement of the receptacle until a predetermined quantity of liquid has collected therein and 35 including an annular member mounted concentrically to the axis of rotation of the swinging receptacle and moving with said receptacle, said annular member having a ratchet notch in one face to provide a tooth, and a pivoted detent engaging said notch, 40 and means yieldingly holding the detent from rotation upon its pivot to thereby hold the receptacle in a raised position until a predetermined quantity of liquid has collected 45 therein.

7. A mechanism of the character de- 50 scribed including a chamber having a liquid outlet, a vertically movable, swingingly mounted receptacle into which said liquid outlet discharges, said receptacle having an outlet valve normally closed but automatically 55 opened by the descent of the receptacle to a predetermined position, a counterpoise yieldingly supporting the receptacle in a raised receiving position, said counterpoise having a weight only slightly greater 60 than the weight of the receptacle itself to cause the return upward movement of the receptacle when the water has been completely 65 discharged therefrom whereby said receptacle will remain lowered until all the liquid has been discharged therefrom, means impeding the downward movement of the receptacle until a predetermined quantity of liquid has collected therein and including an annular member mounted 70 concentrically to the axis of rotation of the swinging receptacle and moving with said receptacle, said annular member having a ratchet notch in one face to provide a tooth, and a pivoted detent engaging said notch, 75 and means yieldingly holding the detent from rotation upon its pivot to thereby hold the receptacle in a raised position until a predetermined quantity of liquid has collected 80 therein.

8. A mechanism of the character de- 85 scribed including a vertically movable receptacle adapted to receive liquid and having an outlet valve, a counterweight yieldingly supporting the receptacle in a raised and receiving position but yielding upon the collection of a predetermined quantity of liquid within the receptacle to permit the descent of the receptacle and the opening of the outlet valve, a member moved by the 90 receptacle as it falls or rises, and a yielding detent engaging said member and yieldingly restraining the movement of said receptacle until the weight of the receptacle and the water thereon overcomes the detent. 95

In testimony whereof I hereunto affix my signature.

JAY GRIFFITH McDOWELL.
